CLAIM

(21) Appl. No.: **29/137,333**

The ornamental design for a transparent box locker door
with single point recessed handle, as shown and described.

(22) Filed: **Feb. 17, 2001**

DESCRIPTION

(51) LOC (7) Cl. **06-06**

FIG. 1 is a front top perspective view of a transparent box
locker door showing our new design;

(52) U.S. Cl. **D6/509**

FIG. 2 is a bottom plan view thereof, the top plan view being
identical to the bottom plan view;

(58) Field of Search D6/397, 432, 433,
D6/436, 437, 438, 440, 441, 445, 446,
448, 491, 470; 312/107, 204, 213, 284,
114, 138.1; 206/557

FIG. 3 is a rear elevational view thereof;

(56) **References Cited**

FIG. 4 is a left end elevational view thereof, the right end
elevational view being identical to the left end elevational
view;
